UNITED STATES PATENT OFFICE.

CHARLES HORVÁTH, OF NEW BRUNSWICK, NEW JERSEY.

COMBINATION BUTTON-FASTENER AND EYELETING TOOL.

1,271,711.

Specification of Letters Patent.

Patented July 9, 1918.

Application filed February 21, 1918. Serial No. 218,421.

To all whom it may concern:
Be it known that I, CHARLES HORVÁTH, a citizen of the United States of America, residing at New Brunswick, Middlesex 5 county, State of New Jersey, have invented certain new and useful Improvements in Combination Button-Fastener and Eyeleting Tools, of which the following is a full, clear, and exact description.

This invention relates to a combination button-fastener and eyeleting tool. One of the objects of my invention is to provide a combination hand-tool for shoe-makers, more especially custom-shoemakers who 15 make shoes to order on a small scale and who do not employ automatic machines. My improved tool is designed for manual operation and is an inexpensive yet efficient implement. To carry my invention into 20 practice, I employ a holder to which any number of different attachments can be applied, said attachments being arranged to secure buttons or eyelets to a shoe. To provide a practicable device, I have designed a 25 special holder arranged so that the different attachments can be applied with rapidity.

I will now proceed to describe my invention in detail, the novel features of which I will point out in the appended claims, 30 reference being had to the accompanying drawings, wherein:—

Figure 1 is an end view of the holder for the different attachments;

Fig. 2 is a side view thereof, illustrating 35 the holder as provided with a punch;

Fig. 3 is an enlarged detail view of the punch;

Fig. 4 is a perspective view of a block containing the anvil for the punch, also a clamp 40 for holding the fasteners for buttons;

Fig. 5 is a similar view of a block containing a holder for an eyeleted hook, for a shoe-lace, and an anvil for an eyelet for a shoe-lace;

Fig. 6 is an enlarged end view of the block illustrated in Fig. 4, looking from the right;

Fig. 7 is an enlarged longitudinal sectional view of the block illustrated in Fig.

5, the section being taken on a line 7—7 in 50 said figure;

Fig. 8 is an end view of the button holding attachment;

Fig. 9 is a side view thereof;

Fig. 10 is a bottom plan view of the button-holder, illustrated as retaining a button;

Fig. 11 is an enlarged view of the eyelet setting tool;

Figs. 12 and 13 are fragmentary diagrammatic views of the operation of the button applying attachments;

Figs. 14 and 15 are similar views of the eyelet setting attachment; and

Fig. 16 is an enlarged diagrammatic view 65 of the manner of applying a hook.

My improved tool comprises a holder consisting of (in this instance) two arms or levers 17 and 18 pivotally connected at 19 and normally kept separated or in an open 70 position by a spring 20. As can be seen in Fig. 2, the arm 17 carries a depending frame-member 21 which carries a forwardly extending support 22 for some of the elements of the combination. The lever 18 is 75 pivoted, intermediate its ends, to the frame-member 21. The forward end of the arm 17 carries a supporting element or lug 23 for a longitudinally movable pin 24 surrounded by a spring 25. The upper end of the pin 80 24 is detachably secured by a screw 26 to a yoke 27 which at its lower end is pivotally connected at 28 to the forward end of the arm 18. The function of the arm 18 is to move the pin 24 longitudinally of its support 23 against the tension of the spring 25. As can be seen, the spring 25 is located between the support or lug 23 and the head 29 of the pin 24. The above named elements constitute the support or holder of 85 my improved device. To punch a hole, apply a button, eyelet or eyeleted hook to a shoe, it is but necessary to equip the holder with the requisite attachments.

As can be seen in Fig. 2, the pin 24 is provided with a threaded socket 30 to receive the threaded shank 31 of a punch 32 (Fig. 3) or the threaded shank 33 (Fig. 11) of a

set 34. For the securement of the blocks 35 or 36 (Figs. 4 and 5) I provide the support 22 on the arm 17 with openings 37 and 38 for the passage of bolts 39 and 40, said 5 bolts engaging threaded openings 41 and 42 in said blocks.

One of the features of my invention is the arrangement of the yoke 27 which is designed to be released from engagement with 10 the pin 24 and swung away therefrom, upon the pivot points 28, in order that said pin 24 can be removed for the application of the punch 32 or eyelet set 34. Should I desire to punch a hole prior to the application 15 of an eyelet, such as is indicated by 43 (Figs. 14 and 15) or an eyeleted hook, such as is indicated by 44 (Fig. 16) I remove the screw 26, swing the yoke 27 away from the pin 24 and withdraw the said pin 24, after 20 which I apply the punch 32 to said pin. After the punch 32 has been applied, I place the pin 24 and punch 32 back in the support 23, move the yoke to its position over the pin 24 and apply the screw 26. 25 To coöperate with the punch, I provide a block, hereinbefore referred to as 35, with an anvil 45, the said block being also provided with a clamp consisting of the resilient arms 46 and 47 to retain a button-fastener 48 to 30 be hereinafter described. For the punching operation the block 35 will be applied to cause the anvil 45 to aline with the punch, as illustrated in Fig. 2. The article to be punched will be placed between the punch 35 and anvil, after which the arms 17 and 18 will be pressed together, causing the punch and anvil to come together, thereby punching a hole in said article.

Should I desire to secure an eyelet, such 40 as 43, to the punched article, or an eyeleted hook, such as 44, I would arrange the device accordingly. To apply an eyelet, such as 43, I remove the punch 32 and apply the set 34, in the manner described for the application 45 of the punch 32. I then remove block 35 and apply block 36, causing the eyelet seat 49 to aline with the set. I then place the eyelet in the hole formed by the punch, and then place the head of the eyelet in the seat 50 49 of the block 36 (see Fig. 14). After the set has been forced downwardly to engage the eyelet, said eyelet will be riveted to the article (a shoe, for instance) as indicated in Fig. 15. Should I desire to apply an eyeleted 55 hook, such as is illustrated by 44 (Fig. 16) I merely reverse the block 36, causing the recessed portion 50 to aline with said set 34, as indicated in Fig. 16. As is indicated in Fig. 5, at each side of the recess 50, I provide shoulders 51, upon which the eyelet portion 52 will rest, the hook portion 44 being inserted into said recess. After the hook 44 has been placed in the recess 50 therefor, or rather when the eyeleted hook

has been placed upon the block, that portion 65 of the shoe containing the hole formed by the punch, can be caused to engage the eyelet portion 52 of the hook, after which the set can be caused to descend and rivet the eyelet 52 to the shoe, as indicated in Fig. 70 16. It will be apparent that the block 36 serves two purposes—that of furnishing an anvil for an ordinary eyelet and that of forming a retainer for an eyeleted hook. The block 35 also serves two purposes, that 75 of providing an anvil for a punch and that of containing a clamp for a button-fastener.

To apply a button to a shoe, neither the punch 32 nor set 34 is required, nor is the block 36. To apply a button, I provide the 80 pin 24 with a post 54 carrying a clamp to retain a button 55 having an eye 56 for the passage of a fastener such as is illustrated in Fig. 6 and indicated by 48. The clamp consists of the yieldable or pressure exerting 85 plates 57 and 58 between which the eye 56 is inserted and clamped. The fingers 57 and 58 are located at each side of the cutaway portion at the lower end of the post 54, as shown in Fig. 9. The round end of the eye 90 56 fits the rounded rear wall 60 of the post of the pocket formed by the said plates 57 and 58. To coöperate with the button-holder, I place the block 35 upon the support 22, causing the fastener-clamp, consisting of the 95 yieldable fingers 46 and 47, to aline with the button-holder (see Figs. 12 and 13). When the button-holder 54 is caused to descend the shank 48 of the fastener will be turned over, having been passed through the eye 56 100 (see Fig. 13) and the portion of the shoe to which the button is to be fastened. After the said shank has been turned over the button will be firmly secured to the shoe. To turn the shank over, I provide the pocket 105 61 of the button-holder with a curved upper wall 62, the said curvature acting to turn the said shank over to form a loop, thereby affixing the button to the shoe.

What I claim as my invention is:

1. A holder consisting of a plurality of pivotally connected arms, a supporting element carried by one of said arms for anvils or the like, a movable pin also carried by said arm located over said support, said pin being arranged for the attachment of a plurality of different tools to coöperate with the different anvils carried by said support, a spring surrounding said pin arranged to restore same to normal position after the 115 operation thereof, a yoke pivotally connected at one end to the other of said arms, and means to detachably connect said yoke to the upper end of said pin.

2. A holder consisting of a plurality of pivotally connected arms, a supporting element carried by one of said arms for anvils or the like, a movable pin also carried by said arm

located over said support, said pin being arranged for the attachment of a plurality of different tools to coöperate with the different anvils carried by said support, a spring surrounding said pin arranged to restore same to normal position after the operation thereof, said yoke being arranged to be swung upon its pivot-points to carry the upper end thereof away from said pin, to

permit of the withdrawal of the said pin, **10** and a removable screw to secure the yoke to said pin.

Signed at New York city, N. Y., this 15th day of February, 1918.

CHARLES HORVÁTH.
